UNITED STATES PATENT OFFICE.

HOWARD A. COOK, OF SOUTHFIELD, MASSACHUSETTS.

FLEXIBLE RAWHIDE RIFLE CLEANER.

Application filed March 23, 1925. Serial No. 17,571.

To all whom it may concern:

Be it known that I, HOWARD A. COOK, a citizen of the United States, and resident of Southfield, county of Berkshire, and State of Massachusetts, have invented certain new and useful Improvements in Flexible Rawhide Rifle Cleaners, of which the following is a specification.

This invention relates to improvements in rifle cleaners, and more particularly to a semi-flexible rifle cleaner composed of flexible rawhide.

One object of this invention is to provide a rawhide rifle cleaner of the above nature which may either be pushed or pulled through the barrel of a gun.

A further object is to provide a rifle cleaner of the above nature which will be simple in construction, inexpensive to manufacture, and very efficient and durable in use.

With these and other objects in view there have been illustrated on the accompanying drawings, several forms in which the invention may be conveniently embodied in practice.

Fig. 1 represents a perspective view of a strip of rawhide from which the first form of rifle cleaner is constructed.

Fig. 2 is a perspective view of the same after it has been twisted into final form, and showing a swabbing cloth in position in the end loop thereof.

Figs. 3 and 4 are perspective views respectively of a modified second form of rawhide rifle cleaner showing its appearance before and after being twisted to final shape.

Figs. 5 and 6 are similar perspective views respectively of a modified third form of rawhide cleaner, before and after being twisted to final shape.

In cleaning gun barrels, it has been customary in the past either to employ a rigid metal ram-rod for pushing a swabbing cloth through the barrel or else to use a string or cord for pulling the swabbing cloth through the barrel. The rigid metal form of rifle cleaner was subject to the disadvantage that not only was it bulky, but it was quite likely to become bent in use, and would thereby scratch the delicate grooves and lands in the bore of the gun barrel. The cord type of cleaner had the disadvantage that in order to obtain a hold on the cord it was first necessary to draw the end of the cord through

the barrel by the use of a weight or other means.

By means of the present invention, the above and other disadvantages have been avoided. This has been accomplished by making the rifle cleaner of solid semi-flexible rawhide. Such a device cannot possibly scratch the bore of a gun and the cleaner may be readily either pulled or pushed through the barrel, at the will of the operator.

Referring now to the drawings, in which like reference numerals denote corresponding parts throughout the several views, the numeral 10 indicates a thin rectangular strip of the original soft "green" rawhide from which the first form of rawhide cleaner is constructed.

A slit 11 is first made adjacent one end of the strip 10, and said slit is spread apart with any suitable tool to an approximately oval shape so as to receive and hold a swabbing cloth by which the bore of the rifle is to be cleaned. The strip 10 will then be twisted in any suitable manner, while still soft, until it assumes a solid cylindrical shape, as shown in Fig. 2 at which time the side edges 12 will lie in a spiral formation and in abutment with one another.

In order to present the least possible obstruction to the passage of the cleaner through the bore, the end of the rod beyond the slit 11 may, if desired, be rounded as shown at 13. The opposite end of the rod is next formed with an enlarged head or knob 14 by means of which the swabbing cloth 15 may be wrapped about that end of the rod in case it is desired to clean the bore with considerable pressure. The next step in the process of manufacture is to allow the rawhide to dry and harden in order to consolidate the fibres thereof. A waterproof coating 16 of any suitable material such as shellac, varnish, or the like, is preferably then applied to the surface of the rawhide.

In Fig. 4 is illustrated a modified form of rifle cleaner which is made from the U-shaped strip of soft "green" rawhide 17 of rectangular cross-section shown in Fig. 3. The side members 18 of the U-shaped strip 17 are twisted about one another, while still soft, until the cleaner assumes a solid cylindrical shape with the abutting edges 20 and 21 of the side members 18 and 19 spirally

arranged in a manner similar to that of the first form of cleaner shown in Fig. 2. A small loop 22 is provided for holding a swabbing cloth 23. This form of rifle cleaner may also be provided with an enlarged head, not shown, similar to the head 14 of the first form shown in Fig. 2, if so desired. It may also be coated with waterproofing as in the first illustrated embodiment.

The form of rawhide cleaner shown in Fig. 6 is made from a narrow strip of soft "green" rawhide originally of the shape shown in Fig. 5. A slit 24 is made near the middle portion of the strip and the end 25 is inserted in said slit and pulled therethrough until only a small cloth holding loop 26 remains.

The side members 25 and 27 are then twisted about one another, while still soft, until a solid cylindrical shape shown in Fig. 6 is produced. As in the previous forms of the invention, the abutting edges 28 and 29 will be arranged spirally around the surface 23 of the cylindrical solid rod and the loop 26 will be left open so as to hold the swabbing cloth as in the two previous forms.

The third illustrated form of rawhide cleaner may be also provided with a waterproof coating and an enlarged knob may be formed on the end opposite from the loop, if desired.

One advantage of the present invention is that the rawhide cleaner is sufficiently flexible to permit it to be rolled up into a small coil when not in use, but at the same time is sufficiently rigid to permit it to be either pushed or pulled through the bore of the gun without bending. It is also sufficiently soft 40 to avoid the possibility of injuring the delicate lands and grooves of the bore.

While the invention herein disclosed is especially adapted for use as a rifle cleaner, it will be understood that it is not limited 45 to such use, but may also be employed for cleaning revolvers, metal pipes, or any other elongated tubular article, within its general principles and scope.

While there have been disclosed in this 50 specification several forms in which the invention may be embodied, it is to be understood that the invention is not to be limited to the specific disclosures but may be modified and embodied in various other forms 55 without departing from its spirit. In short, the invention includes all the modifications and embodiments coming within the scope of the following claims.

Having thus fully described the invention, 60 what is claimed as new, and for which it is desired to secure Letters Patent, is:

1. The process of making a rifle cleaner which comprises forming a cloth-holding loop in one end of a strip of rawhide while 65 said material is still "green" and soft, twist-

ing said strip into solid cylindrical shape with its side edges in abutment, and then allowing it to dry and harden.

2. The process of making a rifle cleaner which comprises forming a cloth-holding loop in one end of a strip of rawhide while 70 said material is still "green" and soft, twisting said strip into solid cylindrical shape with its side edges in abutment, allowing it to dry and harden, and then applying a 75 waterproof coating to the exterior thereof.

3. The process of making a rifle cleaner which comprises forming a cloth-holding loop in a strip of rawhide while said material is still "green" and soft, twisting said strip into solid cylindrical shape with its side edges in abutment, and then allowing 80 it to dry and harden.

4. The process of making a rifle cleaner which comprises bending a rectangular strip of "green" soft rawhide into U-shape 85 twisting the sides of said U-shaped strip about each other into the shape of a solid cylinder with the edges of said strip in abutment, and allowing said cleaner to dry and 90 harden.

5. A semi-flexible rifle cleaner adapted to be either pushed or pulled through the bore of a rifle, comprising a solid rod of dry 95 hardened rawhide, said rod having a loop in one end for holding a swabbing cloth.

6. In a semi-flexible rifle cleaner adapted to be either pushed or pulled through the bore of a rifle, a solid cylindrical rod of dry hardened rawhide, said rod having a loop 100 in one end and being formed by twisting a pair of rectangular strips of soft "green" rawhide upon each other and then allowing said rawhide to dry and harden.

7. A semi-flexible rifle cleaner adapted to be either pushed or pulled through the bore of a rifle, comprising a solid rod of dry hardened rawhide, said rod having a loop in one end for holding a swabbing cloth, 105 said cleaner being formed from an originally flat U-shaped strip of "green" soft rawhide, the sides of said U-shaped strip being twisted upon each other until their edges are in abutment and forming a solid cylindrical rod, the end of said rod having a 110 loop for holding a swabbing cloth.

8. A rifle cleaner comprising a solid cylindrical rod of dry hard rawhide, said rod having a loop at one end and an enlarged knob at its other end, said loop and knob being adapted to interchangeably hold a 115 swabbing cloth for cleaning the bore of a gun, said rod being adapted to be either pushed or pulled through said bore without scratching, and being adapted to be rolled up into a small space when not in use. 120

In testimony whereof, I have affixed my 125 signature to this specification.

HOWARD A. COOK.
